UNITED STATES PATENT OFFICE.

RALEIGH T. KNAPP, OF ROCHESTER, NEW YORK, ASSIGNOR, BY MESNE ASSIGNMENTS,
TO THE SYMINGTON COMPANY, A CORPORATION OF MARYLAND.

DRAFT RIGGING.

Application filed January 19, 1924. Serial No. 687,189.

The invention relates to draft rigging for railway cars and more particularly to an improved form of coupler and yoke connection.

The principal object of my invention, generally considered, is to provide a connection between the yoke and coupler which will permit of relative radial movements between the same and which will at the same time afford an adequate bearing area whereby the strains imparted to the coupler by draft will be transmitted to the yoke in a direct line with the arms thereof.

Another object of the invention is to provide a coupler and yoke connection permitting relative radial movement, said connection being formed by integral projections upon one of the members engaging correspondingly formed slots or recesses in the other member, said parts being so arranged as to permit the assembly and disassembly of said yoke and coupler without subjecting either of the members to strain.

A still further object of the invention is to provide an interlocking radial connection between the coupler and yoke of a simple and inexpensive type and at the same time to afford ample bearing area between the yoke and coupler so that the strains imposed upon either member will be resisted by the other without detriment to said connection.

To these and other ends, the invention comprises the various elements and combination of elements as hereinafter set forth, the novel features whereof are set forth in the appended claims.

In the drawings:

Figure 1 is a top plan view of a portion of the car underframe showing the invention applied thereto;

Figure 2 is a side elevation of the adjacent portions of the coupler and yoke and associated follower, all of which are constructed in accordance with my invention; and

Figure 3 is a view partially in section and partially in plan showing the manner in which the yoke and coupler may be connected and disconnected without strain or spreading the yoke arms.

Throughout the specification and drawings like parts are designated by like reference characters.

Referring to the drawings, the numeral 1 designates the center or draft sills of a railway car which may be of channel form, as indicated. Connected to the inner vertical

faces of the sills is shown the conventional form of stop members 2-2 and 3-3, the former being located adjacent the end of the car (not shown) and are known as the front stops, and the latter the rear stops. It will be understood that this is merely a conventional showing and is simply to illustrate the invention.

Bearing against the front stops 2 is the front follower member 4 and likewise bearing against the rear stops is the rear follower 5. Between the adjacent faces of the followers is a cushioning mechanism 6 of any conventional type, illustrated by dot and dash lines 7. The rear end of the coupler shank 8 is preferably provided with a curved or rounded bearing face 9 adapted normally to engage within a correspondingly formed recess 10 in the front face of the front follower 4. The coupler is preferably provided with lugs 11 extending vertically therefrom, said lugs being preferably cylindrical and being each provided with a substantially rectangular head 12. The heads 12 are arranged with their longer axes substantially at right angles to the direction of length of the coupler shank and their shorter axes are coincident with the diameters of the lugs 11. The curved face 9 of the coupler shank is concentric with the lugs 11.

In order to connect the cushioning mechanism 6 to the coupler under draft, I provide a yoke member 13 of any desired form except that the forward ends of the arms 14 are each extended laterally, as at 15, and are each provided with a slot or opening 16 whose forward end 17 is struck on an arc concentric with the radius of curvature of the lugs 11. As will be observed, the forward ends of the yoke arms 14 are increased in thickness, as at 18, so as to substantially extend the full height of the adjacent lug 11. The thickened portions 18 preferably terminate at a point in line with a plane at right angles to the coupler axis and tangent to the bosses or lugs 11.

To permit the engagement and disengagement of the coupler and yoke above described, without placing strains upon the parts, I form the coupler with rounded edges, as shown at 19, and preferably provide a fillet or fillets 20 between the thickened portions 18 and the normal width of the yoke arms 14.

To assemble the coupler and yoke, the

coupler is placed so that the longitudinal axis thereof is at right angles to the axis of the yoke and the coupler is then given a rotation of 90° from the vertical. The parts 5 are then introduced, as shown in the dotted line position A of Figure 3, and the parts are then rotated into the position B, also shown in dotted lines, and finally into the full line position of this figure. The coupler 10 is then moved bodily longitudinally of the yoke until the lugs 11 are in engagement with the curved surfaces 17 of the slots 16 and the coupler is then rotated on the lugs as a center until its longitudinal axis extends 15 parallel to the longitudinal axis of the yoke and the parts are firmly united. To disassemble the parts the reverse of the operation is performed, it being understood of course that the parts are removed from the car as a unit prior to the disassembly. The dotted line position C merely indicates the possibility of removing the coupler by a rotation in the opposite direction to that described.

20 25 It will be observed that the bifurcated portions of the yoke arms have a combined area equal to the area of the yoke arms at other points. Hence, the total cross sectional area of the yoke is not affected by the slots.

Having now described my invention, what I claim as new and desire to secure by Letters Patent, is:

30 35 40 45 1. In a draft rigging, the combination with a slotted yoke, of a coupler, lugs formed thereon and adapted to extend through the said yoke slots, heads on said lugs, said heads being equal in width to the said yoke slots, the forward ends of the yoke being thickened to extend substantially the full height of the cooperating lugs, said thickened portions being discontinued rearwardly of the forward ends of the slots to permit the separation of said yoke and coupler by a plurality of rotations without spreading of said yoke arms.

50 55 60 65 2. In a draft rigging, the combination with a coupler, of a slotted yoke, means for pivotally connecting the same, said means comprising integral lugs formed on said coupler and adapted to engage within said yoke slots, said projections being adapted to pass through said slots only when the lon-

gitudinal axes of said yoke and coupler are arranged at an angle to each other and when one of said members is rotated about its said axis, the arms of the yoke being decreased in thickness adjacent the rear ends of the slots to facilitate separation of the yoke and coupler.

3. In a draft rigging, the combination with a coupler, of a slotted yoke, means for pivotally connecting said coupler and yoke, said means comprising oppositely disposed headed lugs formed on said coupler and adapted to engage within said yoke slots, said coupler being further provided with rounded edge faces adjacent said lugs, and the inner faces of the yoke adjacent the rear ends of the slots being more widely spaced than adjacent the front ends thereof, said lugs being adapted to be freely entered and removed from said yoke only by a plurality of rotations of said coupler, at least one of said rotations being about the longitudinal axis thereof.

4. In a draft rigging, the combination with a coupler having cylindrical headed lugs projecting therefrom, of a slotted yoke, said yoke slots being each adapted to receive one of the coupler lugs whereby said coupler and yoke are pivotally connected, the cross-sectional area of said yoke arms being at least as great through said slotted portions as in the rear thereof, and means projecting inwardly of said yoke arms adjacent the said slotted portions thereof for increasing their bearing area.

5. In a draft rigging, the combination with a coupler, of a slotted yoke, means for pivotally connecting said yoke and coupler, said means comprising headed cylindrical lugs projecting from said coupler and adapted to pivotally engage the end portions of said yoke slots, the heads of said lugs being adapted to interlockingly engage said yoke arms in the normal position of said yoke and coupler, the inner faces of the yoke being more widely spaced toward the rear ends of the slots to facilitate assembly with and separation from the coupler and a follower within said yoke, said follower and said coupler having cooperating bearing surfaces concentric with said coupler lugs.

In testimony whereof I affix my signature.
RALEIGH T. KNAPP.
